UNITED STATES PATENT OFFICE.

WILLIAM NEWTON BEST, OF NEW YORK, N. Y., ASSIGNOR TO JOHN H. BEST AND EZRA BEST, OF QUINCY, ILLINOIS.

HEATING AND WELDING FURNACE.

No. 893,974.

Specification of Letters Patent.

Patented July 21, 1908.

Application filed April 6, 1904. Serial No. 201,830.

To all whom it may concern:

Be it known that I, WILLIAM NEWTON BEST, a citizen of the United States, a resident of the city of New York, borough of Brooklyn, in the county of Kings and State of New York, have invented new and useful Improvements in Heating and Welding Furnaces, of which the following is a specification.

10 The primary object of this invention is to provide a means whereby an intense and even heat may be maintained in a furnace and whereby such heat can be directed upon the metal or material resting upon the bottom of the furnace.

In furnaces as now constructed, the general tendency is to concentrate the heat at the top of the furnace so that the arch or cover of the furnace is the part which becomes hottest and is more quickly wasted away.

In this connection, the object of my invention is to concentrate the heat at the bottom of the furnace, which is advantageous not only in that the bottom of the furnace may be more easily made resistant to heat than the top thereof, and may be more readily renewed when worn out, but particularly in that the material to be heated will generally rest upon the bottom of the furnace and it is there that the greatest heat is desired.

A further object of the invention is to provide a furnace such that any desired length of straight bars or bent bars can be heated therein.

Other objects of the invention relate to the provision for renewal of the various parts of the furnace and for economical construction and operation thereof.

The accompanying drawings illustrate the invention.

Figure 1 is a plan of the furnace. Fig. 2 is a vertical longitudinal section thereof. Fig. 3 is a rear view of the furnace. Fig. 4 is a transverse section on the line x^4-x^4 in Fig. 2. Fig. 5 is a horizontal section of one of the furnace doors. Fig. 6 is an inside elevation of said door.

50 1 designates a base or foundation which may be made of common brick or any other suitable material. On this base, the fire-

brick floor 2 and fire-brick walls 3 are built up, forming a furnace chamber 4 with an inlet opening in the form of an elongated tunnel 5 and three door openings 6, 7 and 8 lying in substantially the same horizontal plane. A casing or shell 9 of sheet iron surrounds the entire structure, angle-irons 10 being provided at each corner to strengthen the same. 55 At the inlet tunnel 5, the front wall of the furnace is extended as at 11 forming a chamber or inlet tunnel that flares from its outer to its inner end, this extension being incased by a metallic extension 12 of the sheet metal 60 casing of the furnace proper.

13 designates the cover or top of the furnace which is bodily removable from the furnace, having eye bolts 14 whereby it may be lifted off by suitable means. The said 70 top or cover comprises a sheet metal shell or plate 15 lined with fire-brick sections or blocks 16 which are desirably formed as arches having flat bottomed lugs 17 on each end which rest squarely on the side walls of 75 the furnace to give a firm support for the cover, the sheet metal shell 14 having side flanges 18 which extend down and inwardly to hold or lock the fire-brick lining in place. The arch blocks 16 are preferably shouldered 80 or off-set as at 19, the shoulders of adjoining blocks overhanging or engaging with one another to mutually support one another and more effectually prevent passage of heat through the joint.

85 20 designates an oil burner which is preferably of the type shown and described in my Patent No. 752195, dated February 16, 1904, although other forms may be used, this burner being located directly in front of 90 and in line with the inlet chamber 5, and being adapted to direct an atomized blast of hydrocarbon into said chamber from a point above the openings 6, 7 and 8.

An air pressure supply pipe 21 has a controlling valve 22 and a discharge outlet or nozzle 23 located adjacent to the course of the hydrocarbon blast and preferably directly below the same so as to discharge a blast of air into the inlet chamber beneath 100 the hydrocarbon blast.

Each of the openings 6, 7 and 8 is provided with a closure or door 24; these doors are preferably made removable bodily from

the furnace by means of eye bolts 25, each door comprising a casing or shell 26 of sheet metal and a lining 27 of fire-brick or other suitable refractory material. I prefer to 5 make the casing or shell 26 with a flange 28 that tapers inwardly as shown in Fig. 5, so as to hold the lining from inward displacement and also to taper the said shell downwardly so that in case the bottom of the 10 door, which is the part most liable to burn out, burns away, the shape of the casing will retain the rest of the lining from falling down. The furnace wall is made with ledges, brackets, or projections 29 at said openings 6, 7, 8, 15 to receive and support the doors, the taper or inclination of the door bottom causing the door to tip at a slight angle against the furnace wall or against projections or ribs thereon, on each side of the opening. An 20 opening 34 in the flange at the top of the door permits insertion of the fire-brick sections. A spout 30 may be provided at one side of the furnace to draw off slag, said spout communicating with an opening 31 in 25 the furnace wall. The bottom of the heating chamber 4 is preferably below the inlet 5 and may be covered with sand or other refractory material to form an easily renewable layer protecting the fire-brick below, 30 from the action of the heat.

In using the furnace, the oil and steam blast is turned on by oil and steam pipes 32, 33, at burner 20 thereby producing a blast or jet of atomized liquid fuel which burns 35 within the inlet chamber or tunnel 5, the latter forming an expansion and combustion chamber.

It will be understood that the furnace is particularly intended for heating and reheating iron and steel to enable the same to 40 be worked under hammers, rolls and the like. In some of such operations it will be sufficient to use the burner alone, without the use of the air blast. In case the iron is 45 to be heated to welding heat or, if for any other reason, a high temperature is desired, the air blast is turned on at nozzle 23 and issues in a jet or stream of considerable force directly beneath and parallel to the issuing jet 50 or stream of atomized oil. I prefer to use a considerable pressure, say, 80 pounds or more, so that the air jet will have a very high velocity. I have found that with such an air blast disposed in this manner, the 55 combustion is not only more perfect but is concentrated on the bottom of the furnace or upon the material placed upon the bottom of the furnace. It will, therefore, be seen that I use a burner to atomize the liquid 60 fuel and an air blast, or forced draft, to cause the combustion to take place from below the fuel, thus to force the flame upon the metal or part to be heated in order to concentrate the heat. The superheating combustion

chamber 5 flares inwardly and enables the 65 expansion of the flame to assist it into the furnace, and prevent any explosion of the flame from the outer end of said chamber.

The doors 24 will be placed in position or removed as may be required by the work in 70 hand, thus, in case a long straight bar, rail or bundle is to be heated, the two side doors may be removed and the material inserted therethrough, while if a bent bar or rail is to be heated, one side and one end door may 75 be removed to enable insertion of the same. The furnace chamber having three openings, two of which are opposite and parallel to one another, while the third is intermediate and transverse to the others, enables straight 80 or bent articles to be inserted as stated.

It will be understood that the furnace can be built in any desired size or shape to adapt it to particular purposes, and the construction and arrangement of the parts may be 85 modified in various ways without departing from my invention.

I have found in practice that by the use of the superheating chamber, above described, the combustion therein is so perfect that 90 there is no flame in the furnace proper.

By the term heating-furnace and heating chamber, I mean any furnace or chamber intended or adapted for the heating or melting of metal or any other material.

It is to be noted that the furnace chamber is closed throughout above the level of the inlet tunnel 5. In practical operation, the metal to be welded or heated for any purpose will be placed upon the floor of the chamber, 100 thus being below the level of the inwardly-flaring tunnel, and when the doors are closed the burner and air-jet may be started into operation, whereupon the fuel is injected into the chamber, and being there ignited, the 105 combustion takes place, and as the air nozzle injects air underneath the inflowing fuel, the combustion takes place with great intensity from the underside of the injected fuel. The upper portion of the chamber being closed 110 to the external air, and the atmospheric air being able to reach the same only by passing upward through the fuel, the combustion of the fuel is more intense toward the floor of the furnace than toward the top of the furnace, so that the heat is thereby forced downward upon the material on the floor of the furnace. By this arrangement the heat is 115 directed evenly downward upon the floor and upon the objects thereon, thus effecting very 120 rapid and even heating of the same.

What I claim is:—

A furnace comprising a chamber provided on one side with an elongated inwardly-flaring tunnel and on other sides with openings 125 and with closures for said openings, the chamber being provided with a floor below the level of the tunnel and being closed

throughout above the level of said tunnel, an oil burner to direct flame through the tunnel into the chamber, and an air nozzle below the oil burner to inject air beneath the fuel into 5 the chamber.

In testimony whereof, I have signed my name to this specification in the presence of

two subscribing witnesses at Los Angeles, in the county of Los Angeles and State of California, this 29th day of March, 1904. 10

WILLIAM NEWTON BEST.

In the presence of—

ARTHUR P. KNIGHT,
JULIA TOWNSEND.
